(57) **CLAIM**

I claim the ornamental design for combination eyeglass case and eyeglass strap, as shown and described.

DESCRIPTION

FIG. 1 is a top, front, right side perspective view according to the claimed design;

FIG. 2 is a top plan view thereof;

FIG. 3 is a front view thereof;

FIG. 4 is a left side view thereof (the right side being a mirror image);

FIG. 5 is a rear view thereof;

FIG. 6 is a bottom plan view thereof; and

FIG. 7 is a top, front, right side perspective view in open condition; and,

FIG. 8 is a top, front, right side perspective view thereof, showing the strap in a detached position.
